WALTER W. SHORDAY, OF LAWNDALE, PENNSYLVANIA.

VALVE.

1,418,482.

Specification of Letters Patent. Patented June 6, 1922.

Application filed August 11, 1920. Serial No. 402,822.

To all whom it may concern:

Be it known that WALTER W. SHORDAY, a citizen of the United States, residing at Lawndale, in the county of Philadelphia, and State of Pennsylvania, has invented certain new and useful Improvements in Valves, of which the following is a specification.

My invention relates to improvements in sectional valves adapted to govern the flow 10 of gasoline from a tank.

The principal object of my invention is to provide a valve of the class described, adapted to be positioned in an opening or port of a gasoline tank in such a manner as to permit 15 of the flow of gasoline therefrom until a predetermined level in the tank is reached when the flow is automatically checked until released.

Other objects and advantages of this invention will be apparent during the course 20 of the following description.

In carrying out the objects of the invention generally stated above, it will be understood of course, that the essential features of 25 the same are necessarily susceptible of changes in detail and structural arrangements, preferred and practical embodiments of which are shown in the accompanying drawings, wherein:-

30 Figure 1 is a transverse sectional view of a conventional gasoline tank illustrating the valve assembled and positioned therein, the portion of the valve within the tank being shown in section;

35 Figures 2, 3 and 4 are detailed vertical views of the three separate members comprising the valve, the same being arranged in consecutive order and in position for assembling;

40 Figure 5 is a perspective elevational view of the assembled valve in position in the tank with a conventional sediment bulb attached to the base of said valve, and

Fig. 6 is a vertical elevational view, 45 partly in section, of the upper member K of the valve, illustrating the flare adjacent the base thereof to provide for a tight connection with the member P; and

Figures 7 and 8 are vertical elevational 50 views of the members P and T illustrating circular ports Z therein.

Like reference characters refer to like parts throughout the drawings.

Referring to said drawings in detail the character J denotes the lower portion of a conventional gasoline tank, provided with the opening or port J' therein.

The valve comprises the three separate cylindrical members or sections K, P and T, shown in the drawings as Figs. 2, 3 and 4. 60 Said cylindrical members K, P and T are each provided with an opening or port L, Q and U, respectively. These ports are preferably made square but may be formed circular as indicated in dotted lines in Figs. 65 1, 2, 3 and 4 and in full lines in Figs. 6, 7 and 8 of the drawings and designated by the reference character Z.

The valve is assembled and positioned as follows: The member K is inserted in the port J' of the tank J and is exteriorly threaded above its flanged base N, said threads being designated by the reference character M, to engage the interior threads J² provided in the said opening J'; member P is then inserted within member K but does not extend completely therethrough, member T is inserted within member P and is provided at its top with the exterior threads S to engage interior threads provided adjacent the top of member K as shown by dotted lines in Fig. 1 and indicated by the reference character X. The member P has provided on its base the transversely extending handles R, and the members K and T are each provided with hexagonal flanged bases designated by the characters N and V, respectively.

The members K and T being threaded in position are thus fixed in position and the member P is vertically positioned therebetween, as above described, and said member P is prevented from being displaced by being disposed between the transversely extending flanges N and V of the members K and T, 90 but is movable between said members by means of the handles R.

The hexagonal flange V on the member T is interiorly threaded to engage the exterior threads of a conventional sediment bulb 100 Y usually positioned at the bottom of gasoline tanks on gravity feed systems.

The member K, adjacent its base, is flared as indicated by the reference character G. The members P and T are similarly flared as indicated by the reference characters G' 5 and G², respectively, so that when the members K, P and T are assembled in position, these flared portions provide a tight connection therebetween and prevent any leakage or escape of the gasoline except through 10 the ports L or Z.

When the valve is assembled and in position in the tank J the ports L and U will register or communicate with each other and the port Q is put in and out of communication with said ports L and Q by 15 partially rotating the member P by means of the handles R; said ports being even with the bottom of the tank. The ports L and U are fixed in position when the valve is 20 assembled and in position while the port Q is movable.

In operation the valve is assembled and placed in position, as hereinbefore described, in the opening or port J' of the tank J, the 25 upper section of the member K projecting upwardly from the bottom of the said tank, the port Q is placed in the off or out of register position by partially rotating the member P, the various ports, as aforesaid, 30 being even with the bottom of the tank. The gasoline will flow through said valve until it reaches the level of the upwardly projecting portion of the member K when it will cease to flow by reason of said projecting 35 portion, thereby reserving a supply of gasoline in the bottom of the tank, the amount reserved being regulated by the extent of the distance the upper portion of the member K projects from the bottom of the tank; 40 this is in turn, obviously, regulated by the length of the upper section of said valve. I find in practice with the average automobile tank that if the projection extends one and three-quarters inches above the bottom 45 of the tank it will reserve approximately one gallon of gasoline. With the valve in use on an automobile gasoline tank when the gasoline ceases to flow as above described the motor stops thereby indicating to the 50 operator that he has but a limited amount of gasoline in the tank. By partially rotating the member P to the on position or in register position the balance of the gasoline in the tank will flow through said valve until 55 the tank is drained.

This valve is designed to reserve about one gallon of gasoline in the tank as aforesaid which should be sufficient to run the average motor from ten to fifteen miles, in 60 which distance the operator may be enabled to obtain a fresh supply of gasoline.

As before said the valve is opened or closed by partially rotating the member P by means of the handles R to an off or on position, 65 i. e., by bringing the ports L, Q, and U.

into and out of register or communication with each other. The said member P is susceptible of a semi-circular rotation and the said ports are brought into and out of register by partially rotating said member 70 P from one extreme to the other; these positions being governed by the limit stop or projection O on the flanged base N of section K.

Having thus described my invention what 75 I claim as new and desire to secure by Letters Patent is:—

1. A valve adapted to be connected to a tank to regulate the flow therefrom, comprising three separate cylindrical members, 80 the upper member thereof being adapted to be secured in an opening in the base of said tank, the remaining members being adapted to fit within said upper member, means to retain said members in position, ports in 85 said members and means to position said ports in and out of communication with each other, substantially as described.

2. A valve adapted to be connected to a tank to regulate the flow therefrom, comprising three separate cylindrical members, 90 the upper member thereof being adapted to be secured in an opening in the base of said tank and extending upwardly therein from the base thereof, the remaining members 95 being adapted to fit within said upper member, means to retain said members in position, ports in said members and means to position the port in the central member out of communication with the ports in the 100 other two members, whereby the flow from the tank is automatically checked when it reaches the level of the upwardly projecting first mentioned valve member, substantially as described.

3. A valve adapted to be connected to a tank to regulate the flow therefrom, comprising three separate cylindrical members, the upper member thereof being adapted to be secured in an opening in the base of said tank 110 and extending upwardly therein from the base thereof to a predetermined height, the remaining members being adapted to fit within said upper member, means to retain said members in position, ports in said members, means to position the port in the central cylindrical member out of communication with the ports in the other two members whereby the flow from said tank is automatically checked when it reaches the lev-

el of the upwardly extending first mentioned valve member thereby providing means to reserve a predetermined amount of liquid in the said tank, substantially as described.

4. A valve adapted to be connected to a tank to regulate the flow therefrom, comprising three separate cylindrical members, the upper member thereof being adapted to be secured in an opening in the base of said 130

- 5 tank and extending upwardly therein from the base thereof to a predetermined height, the remaining members being adapted to fit within said upper member, means to retain 65
 5 said members in position, ports in said members, means to position the port in the central cylindrical member out of communication with the ports in the other two members, whereby the flow from said tank is 70
 10 automatically checked at a predetermined level governed by the extent the said first mentioned valve member projects upwardly from the bottom of said tank, substantially 75
 as described.
- 15 5. A valve adapted to be connected to a tank to regulate the flow therefrom, comprising three separate cylindrical members, the upper member thereof being adapted to be secured to an opening in the base of said 80
 20 tank and extending upwardly therein from the base thereof to a predetermined height, the remaining members being adapted to fit within said upper member, means to retain 85
 25 said members in position, ports in said members, means to position the port in the central member in and out of communication with the ports in the other two members, whereby the flow from the tank is automatically checked when it reaches the level 90
 30 of the upwardly extending first mentioned valve member when said ports are out of communication thereby reserving a predetermined amount of liquid in the said tank until the said ports are positioned in 95
 35 communication with each other, substantially as described.
6. A valve adapted to be connected to a tank to regulate the flow therefrom, comprising three separate cylindrical members, 100
 40 an upper or outer member, an inner or lower member and a central member therebetween, the upper member thereof being adapted to be secured in an opening in the base of said tank, the remaining members 105
 45 being adapted to fit within said upper member, means to retain said members in position, ports in said members, said upper member and the port therein and said lower member and the port therein being fixed in 110
 50 position the ports communicating, the said central member and the port therein being movable between said upper and lower members whereby the port in said central member may be positioned in and out of 115
 55 communication with the ports in the said upper and lower members, substantially as described.
7. A valve adapted to be connected to a tank to regulate the flow therefrom, comprising three separate cylindrical members, an upper or outer member, an inner or lower member and a central member therebetween, the upper member thereof being adapted to be secured in an opening in the base of said 120
 60 tank, the remaining members being adapted to fit within said upper member, means to retain said members in position, the said upper and lower members being fixed in 125
 position and having ports therein communicating with each other, a port in the said central member, means secured to said central member to partially rotate it between said upper and lower members so that the port therein may be brought in and out of communication with the said ports in said upper and lower members and means to limit in either direction the partial rotation of said central valve member, substantially as described.
8. A valve adapted to be connected to a tank to regulate the flow therefrom, comprising three separate cylindrical members, an upper or outer member, an inner or lower member and a central member therebetween, the said upper member being provided with a flanged base and exteriorly threaded above 130
 85 said flanged base to engage an interiorly threaded opening provided in the base of said tank, the central member thereof being adapted to fit within said upper member, but not extending completely therethrough, between the flanged bases provided on the upper and lower members, respectively, and the said lower member being adapted to fit within the said central member it being exteriorly threaded at its top to engage interior threads provided on the upper portion of the said upper member, whereby the said upper and lower members are fixed in 135
 90 position and the said central member is 140
 movable therebetween, ports in said three valve members, means provided on the base of said central member to partially rotate it between the said upper and lower members to position the port in said central member 145
 in and out of communication with the ports in said upper and lower members, substantially as described.
9. A valve adapted to be connected to a tank to regulate the flow therefrom, comprising three separate cylindrical members, an upper or outer member, an inner or lower member and a central member therebetween, the said upper member being provided with a flanged base and exteriorly threaded above 150
 110 said flanged base to engage an interiorly threaded opening provided in the base of said tank, the central member thereof being adapted to fit within said upper member, between the flanged bases provided on the upper and lower members, respectively, and the said lower member being adapted to fit within the said central member it being exteriorly threaded at its top to engage interior threads provided on the upper portion of the said upper member, whereby the said upper and lower members are fixed in 155
 120 position and the said central member is 160
 125

movable therebetween, ports in said three valve members, means provided on the base of said central member to semi-circularly rotate it between the said upper and lower members to position the port in said central member in and out of communication with the ports in said upper and lower members,

said flange on the base of said lower member being interiorly threaded to engage the exterior threads of a sediment bulb, substantially as described. 10

In testimony whereof I affix my signature.

WALTER W. SHORDAY.
